UNITED STATES PATENT OFFICE.

JAMES LEON WILLIAMS, OF PELHAM, NEW YORK, ASSIGNOR TO THE DENTISTS' SUPPLY COMPANY, A CORPORATION OF NEW YORK.

CROWN-TOOTH AND PIN THEREFOR.

1,149,239.

Specification of Letters Patent. Patented Aug. 10, 1915.

Application filed March 6, 1915. Serial No. 12,485.

To all whom it may concern:

Be it known that I, JAMES LEON WILLIAMS, a citizen of the United States, and resident of Pelham, county of Westchester, 5 and State of New York, have invented an Improvement in Crown-Teeth and Pins Therefor, of which the following is a specification.

This invention relates to crowns for teeth 10 and more particularly to the pin for holding the tooth crown to the root of the tooth, and my object is more especially to provide a construction in which the tooth crown shall be so supported and attached to the root 15 that a greater strength of union is secured than in the customary practice heretofore employed, and moreover to provide a construction of pin which shall give great stability against displacement of the tooth, 20 which displacement has heretofore been possible by the bending of the pin.

My object is also to provide a pin in which the prong entering the root and the prong secured in the crown tooth is offset suffi- 25 ciently to enable the latter prong to extend down in the direction of the biting or incisor edge of the tooth in the case of front teeth, so that a greater length of pin may be em- 30 ployed and be surrounded with a more sub- stantial portion of the porcelain.

My object is also to so shape the pin at the juncture of the tooth prong and the root prong that it shall provide a rearwardly ex- 35 tends heel for receiving the upward thrust of the lingual portion of the tooth to pre- vent rotation of the tooth relatively to the root by the bending of the pin, and more- over to provide a pin structure which will effectually prevent the possible rotation 40 of the tooth upon the pin about a vertical axis, the construction being such that the pin cannot possibly turn in the porcelain tooth structure.

With the above and other objects in view, 45 the nature of which will be more fully un- derstood from the description hereinafter, the invention consists in the novel construc- 50 tion of the pin and its combination in associa- tion with the tooth as hereinafter more fully described and defined in the claims.

Referring to the drawings: Figure 1 is a 55 vertical section through a tooth-root and a tooth crown secured by a pin embodying my invention; Fig. 2 is a front elevation of the

same; Fig. 3 is a plan view of the tooth 55 crown showing the recess for the pin; Fig. 4 is a vertical section through the tooth crown on $y-y$ of Fig. 3 and line $x-x$ of Fig. 1, with the pin removed; Fig. 5 is a perspective view of my improved pin; Fig. 60 6 is an enlarged top view of the same; and Fig. 7 is a perspective view of the tooth crown.

Heretofore in practice it has been cus- 65 tomary to provide the tooth crown with a pin having an extending prong for inser- 70 tion into the root of the tooth, in which the prong was in alinement with the pin portion within the tooth structure. Furthermore, it is customary to bake the pin in the crown 75 so that the pin is a unitary structure with the tooth crown. Where the pin is in this manner rigidly connected with the porce- 80 lain crown it is often necessary to bend the prongs to insure proper positioning of the 85 crown in the mouth. This weakens the con- struction both by possible injury to the pin and to the angularity given thereto. Fur- 90 thermore, in teeth as heretofore made em- ploying straight pins, the location of the 95 pin in the porcelain crown, to adapt it to the root, has caused the pin to be located ob- jectionably far to the lingual side of the tooth; and to secure the proper strength, it has been necessary to increase the porcelain 100 at this place and thus deviate from the nat- 105 ural shape of a tooth to a more or less objec- tional degree.

By the construction of my improved crown and pin I am enabled to overcome the above 90 recited objections inherent in the former practice, and in accomplishing this I pro- 95 vide a pin structure in which the tooth prong and the root prong are definitely offset and the metal at the juncture of these prongs 95 is widened, more particularly in the direc- 100 tion of the offset to provide a heel at the rear of the prongs to engage the crown to- 105 ward the lingual side, and thereby more strongly brace the crown against displace- ment under hard usage, prevent any possible capacity of the porcelain crown to rotate upon the pin, and to provide full engage- ment between the pin and the crown without abnormal or excess porcelain at the rear or 105 lingual side. Moreover, the metal in the pin is so thickened at the junction between the crown and the root that there is no possi-

bility of its bending under undue stress. Furthermore, the construction of my improved pin and crown is such that the pin may be employed separate from the crown, and after being cemented into the root the crown may be cemented to the pin and in position upon the root and adjusted to the proper position without any necessity of bending the pin.

More specifically referring to the drawings, 7 represents the root prong of the pin, which is substantially coaxial with a quasi-triangular reinforcement or enlargement 8. Projecting downwardly from the base of the enlargement 8 is a crown prong 9, the axis of which prong is substantially parallel to the axis of the root prong 7, and said prong 9 is located at the forward part of the base of the substantially triangular enlargement 8, and therefore the prongs 7 and 9 are in effect offset with respect to each other. The base of the enlargement 8 is also provided with a short downward projection 10 located at the rear part of the base and opposite to where the crown prong 9 is located. Therefore, the said projection 10 and prong 9 are opposite each other and in substantially parallel planes and the said projection 10 may be said to extend from the heel of the enlargement or reinforcement 8 and which heel and projection act as a brace for the tooth crown against backward thrust.

The tooth crown 11, which is to be fitted with the pin, is provided with a suitable deep bore 12 adapted to receive the prong 9, and with a substantially trapezoidal or other suitable shallow recess 13 into which fits the lower or base part of the reinforcement portion 8. This recess 13 of the crown, at the bottom and adjacent the side opposite the deep bore 12, is provided with a pocket 14 adapted to receive the heel projection 10 of the pin. It will be seen from Fig. 1 that by offsetting the prong 9 from the prong 7, the bore 12 for the prong 9 in the crown 11, is formed near to the front or labial part thereof, therefore leaving more material for the rear of the crown into which the heel may be stepped. This is of great importance, as the maximum stress applied to the crown is always from the rear, toward the front, and therefore the crown is greatly strengthened when the bore 9 is made nearer to the front than to the rear, or contrary to what has heretofore been the general practice. By engaging the heel projection 10 at the rear of the crown pin with the pocket 14 in the crown, I further brace the crown at the rear. The reinforcement or body 8 having its base fitting into the shallow recess 13 while its prong 9 fits down into the bore 12 and its heel projection into the pocket 14, makes a strong connection when cemented in place and prevents any dis- placement by torsional action.

Attention is called to the fact that in the preferred form of my improved pin the heel portion at the junction of the crown and root prongs is substantially dovetail in shape, as can be easily seen, more particularly in Figs. 2, 5 and 6. The heel reinforcement, which projects into the pocket 14 of the cavity 15 of the crown locks the pin to the crown when the cement is made to bind the crown with the root, as best seen in Fig. 1. That is to say, the cement 19 filling the cavity 15 and pocket 14 seals the crown pin to the crown and supplements the cementing of the prong 9 in the bore 12 thereof. The partly engaged base of the reinforcement 8, and also the heel projection 10, prevent the turning of the crown pin in the crown. The prongs 7 and 9, either or both, may be indented or serrated as at 18, if desired to more strongly hold in the cement 85 within the bore 12 of the crown and bore 16 of the tooth root 17.

The pin may be made of any suitable metal or metal alloy or of a plated or coated metal if so desired, as I do not restrict myself in this regard. These pins may be cast, forged, or stamped from sheet metal; the latter with a forging action to shape the parts is preferable, both because it produces a cheaper and stronger pin than by other methods of manufacture.

From the foregoing description, taken in connection with the accompanying drawings, the advantage of the construction of my improved pin and crown, separately and combined, will be readily understood by those skilled in the art to which the invention pertains; and it will be appreciated that the advantage of this improvement is that it effects a more widely distributed and better balanced hold of the pin on the porcelain crown, and gives a far stronger and more secure attachment to the natural root than the method of attachment heretofore employed in practice.

I have shown the construction of my improved crown and pin which I deem preferable, but I do not restrict myself to the minor details, as these may be modified without departing from the spirit of the invention.

Having now described my invention, what I claim as new and desire to protect by Letters Patent is:

1. A crown pin having a root prong, a substantially triangular reinforcement portion coaxial with the root prong and having its lower end extending both to the front and to the rear of the root prong, said reinforcement portion having at the rear of its base a short heel projection, and at the forward end of its base a crown prong having its axis substantially parallel to the axis of the root prong but out of axial alignment therewith.

2. A crown pin having a crown prong and a root prong, and a reinforcement portion between and uniting said prongs, the crown prong being at one end of the base of said reinforcement and offset from the axis of the root prong and said reinforcement portion having a dovetail heel projection at the other end of the base thereof.
3. A crown pin having a crown prong and a root prong, and a downwardly projecting heel projection arranged rearwardly from the junction of the said crown and root prongs, all of the pin except the heel projection being of substantially uniform
- 5 thickness and the heel projection being of 15 greater thickness at its lower part.
4. A tooth crown having its end which comes next to the root provided with a deep bore and a rear pocket of greater width and greatly less depth than the bore and 20 connected therewith by a shallow recess.

In testimony of which invention, I hereunto set my hand.

JAMES LEON WILLIAMS.
